(21) Appl. No.: **29/479,642**

Primary Examiner — Jeffrey D Asch

(22) Filed: **Jan. 17, 2014**

(74) Attorney, Agent, or Firm — Robert E. Bushnell, Esq.

(30) **Foreign Application Priority Data**

(57) **CLAIM**
The ornamental design for a mobile phone, as shown and described.

Jul. 18, 2013 (KR) 30-2013-0037241

DESCRIPTION

(51) **LOC (10) Cl.** **14-03**

FIG. 1 is an oblique view of the mobile phone showing my new design in a closed position;

(52) **U.S. Cl.**

FIG. 2 is a front view thereof;

USPC ..... **D14/138 G**

FIG. 3 is a rear view thereof;

(58) **Field of Classification Search**

FIG. 4 is a left side view thereof;

CPC H04M 1/02; H04M 1/0202–1/035;

FIG. 5 is a right side view thereof;

H04M 1/0235; H04M 1/0237; H04M 1/0239;

FIG. 6 is a top view thereof;

H04M 2250/22; H04M 1/03; H04M 1/23;

FIG. 7 is a bottom view thereof;

H04M 1/72519; G06F 1/1626

FIG. 8 is a front view illustrating a second embodiment the mobile phone, the only difference compared to the first embodiment is that the buttons disposed at the upper and lower portions are asymmetrical; and,

USPC ..... D14/138 G, 138 AD, 138 R, 496, 203.1,

FIG. 9 is a front view illustrating a third embodiment of the mobile phone, the only difference compared to the first embodiment is that there is only a single button disposed at an upper portion.

D14/203.3, 203.5, 203.7, 248, 218, 341,

The broken lines shown in FIG. 3 that are immediately adjacent to the shaded areas, and define an unshaded region,

D14/138 AC; 455/575.1, 556.1, 556.2,

represent the bounds of the claim, while the broken lines within the boundary are directed to environment. The broken

455/575.3, 575.4, 566; D21/517, 329, 331;

579/433.01, 433.04; D13/168;

379/433.01, 433.04; D13/168;

361/679.3, 679.56; D10/65, 78

361/679.3, 679.56; D10/65, 78

See application file for complete search history.

361/679.3, 679.56; D10/65, 78
